UNITED STATES PATENT OFFICE

CHARLES E. NYGAARD, OF PHILADELPHIA, PENNSYLVANIA

OPERATION CHART AND INDICATOR

Application filed June 13, 1931. Serial No. 544,151.

My invention relates to an operation chart and indicator for carrying out a process having different steps of progression during the operation.

- 5 While the invention is intended for general use it is especially well adapted for use in connection with a laundry clothes washer, commonly referred to in the trade as a "washing wheel."
- 10 It is well known that from the time clothes are placed in a washer until the clothes are removed they are subjected to different processes during the washing operation. During this operation the height of 15 the water in the washer is changed several times as well as the temperature of the water and for each step or process during the washing operation the washer is operated a predetermined period of time. It is customary 20 for an operator of a washer to have an alarm clock which is set at the beginning of each step during the washing operation and sounds an alarm at the end of the respective step which is for a predetermined period of 25 time. The number of steps during a washing operation are varied depending on the kind of clothes being washed. Due to the large number of different steps in a washing operation, it is very easy for the operator 30 to become confused as to the stage of the washing and particularly when he has a number of washers to look after. Furthermore, the operator must remember whether the articles being washed are of a light or dark 35 color and if the articles being washed are personal clothes, such as hotel "guest" work, hotel "flat" work, "family" wash, overalls, or of any other classification used by the trade.
- 40 The invention as illustrated is designed for use in connection with a laundry washer and includes an operation chart on which appears the different steps to be performed during a washing operation, the height of the water in the washer, the temperature of the water and the number of minutes the washer is to be operated during each step of the operation. The invention further provides an indicator that may be manually set to indicate the current step in a washing operation

together with "cut-out" indicators for certain of the steps during the operation for different classes of work.

By the use of this invention an operator by looking at the chart may tell at a glance the different steps to follow in carrying out a given washing operation and the indicator will denote the current step in the operation so that operators may be changed during a washing operation without confusion as to the kind of clothes being washed or as to how far the operation has proceeded.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a front elevation of the invention; Fig. 2 is a perspective view of the indicator plug; and

Fig. 3 is a perspective view of one of the cut-out plugs.

The numeral 4 indicates a wall to which a panel 5 is secured by screws 6. Mounted on the left hand end of the panel 5 is a clock 7 having an alarm that may be set to operate at the end of a very short period of time. This alarm includes minute graduations 8 from "0" to "10" and a cooperating pointer 9 which may be set, at will, to determine the period of time at the end of which the alarm will be sounded and an "on" and "off" lever 10 for the alarm.

In the center of the panel 5 is a sectional washing chart made up of a main card 11 and a plurality of secondary cards 12. The main card 11 is removably mounted in a main holder 13 and the secondary cards 12 are removably and individually mounted in secondary holders 14. These holders 13 and 14 are secured to the panel 5, vertically spaced, the one below the other, with the main holder 13 at the top.

The following indicia appears on the main card 11, reading from the left to the right: "Operation", "Height of water", "Temp. of water", and "Mins. to run". The abbrevia-

75

tions "Temp." and "Mins.", of course, are for "temperature" and "minutes". Printed on the secondary cards 12, reading from the top down, are the different steps or processes to be followed in washing clothes. The secondary cards 12 also have printed thereon in a vertical column under "Height of water" numerals indicating the height of water in the washer for each step in the operation. A vertical column of numerals also appears on the cards 12 under "Temp. of water" indicating the temperature of the water in each of said steps, and under "Mins. to run" is a vertical column of figures representing the number of minutes for each step of operation. It will be noted that each secondary card 12 is made in section so that the indicia may be changed, at will.

On the right hand end portion of the panel 5 is an indicator comprising a horizontal row of holes 15 in said panel for each secondary holder 14. As shown, there are four holes 15 in each horizontal row and these holes are arranged in vertical rows. Horizontally aligned with the holder 11 is a holder 16 secured to the panel 5 and having a removable card 17 and which holder is placed directly over the several vertical rows of holes 15.

The following indicia appears on the card 17, reading from the left to the right: "Guest work", "Hotel", "Light colors" and appear directly over the first three vertical columns of holes 15. Any suitable indicia may be placed on the card 17 over the last vertical row of holes 15.

An indicator plug 18 adapted to be placed in any one of the holes 15 is attached by a cord 19 to the panel 5. The vertical row of holes 15 in which the indicator plug 18 is placed indicates the type or class of clothes being washed while the horizontal row indicates the current step in the washing operation. The indicator plug 18, as positioned, indicates that the washing is for a hotel and the washing is in the third rinsing process.

When certain steps in the washing operation are to be eliminated, cut-out plugs 20 are placed in the respective holes 15. As shown under Hotel, the third and last three steps of the washing operation are cut-out by the plugs 20.

In starting a washing operation the operator places the indicator plug 18 in the uppermost open hole 15 in the vertical column under the type or class of clothes to be washed and as each successive step in the operation is completed he moves the indicator plug 18 downward and into the next open hole 15.

60 What I claim is:

1. A chart for a series of given operations, each operation having different steps of progression and including a heading indicating a requirement for the operation, indicia indicating the different steps of progression in

each operation, and a symbol for each step in each operation and indicating the ratio for the requirement, in combination with an indicator for the current step in a given operation.

2. A chart for a given operation having different steps of progression and including a heading indicating a requirement for the operation, indicia indicating the different steps of progression in the operation, a symbol for each step in the operation and indicating the ratio for the requirement, in combination with an indicator for the current step in the operation, and a shiftable cut-out indicator for any one of the steps in the operation.

3. A chart for a series of given operations, each operation having different steps of progression and including headings indicating different requirements in each operation, indicia indicating the different steps of progression in each operation, and symbols for each step in each operation and indicating the ratio for each requirement, in combination with an indicator for the current step in a given operation.

4. A chart for a series of given operations, each operation having different steps of progression and including headings indicating different requirements in each operation, indicia indicating the different steps of progression in each operation, and symbols for each step in each operation and indicating the ratio for each requirement, in combination with an indicator for the different steps in each operation including a relatively fixed element for each step in a given operation and having a designating relation thereto, and a shiftable indicating element applicable to anyone of the fixed elements to indicate the current step in a given operation.

5. The structure defined in claim 4 which further includes a cut-out indicating element applicable to any one of the fixed elements for a given step in the operation.

6. A chart for a series of given operations, each operation having different steps of progression and including headings indicating different requirements in each operation, indicia indicating the different steps of progression in each operation, and symbols for each step in each operation and indicating the ratio for each requirement, in combination with a panel having a hole for each step in each operation and having a designating relation thereto, and an indicating plug insertable into any one of said holes to indicate the current step in a given operation.

7. A chart for a given operation having different steps of progression and including headings indicating different requirements in the operation, indicia indicating the different steps of progression in the operation, and symbols for each step of the operation and indicating the ratio for each requirement, in

combination with a panel having a hole for each step in the operation and having a designating relation thereto, an indicating plug insertable into any one of said holes to indicate the current step in the operation, and a cut-out indicating plug insertable into any one of said holes for a given step in the operation.

8. A chart for a given operation having 10 different steps of progression and including headings indicating different requirements in the operation, indicia indicating the different steps of progression in the operation, and symbols for each step of the operation and 15 indicating the ratio for each requirement, in combination with a series of headings each indicating a different class of work, a relatively fixed element under each heading for each step in the operation and having a designating 20 relation thereto, of a shiftable indicating element applicable to any one of the fixed elements to indicate the class of work and the current step in the operation.

9. A chart for a given operation having 25 different steps of progression including a panel having a main holder, and a plurality of secondary holders, said main and secondary holders being vertically spaced, a card in each holder, a heading on the card in the main 30 holder indicating a requirement for the operation, the cards in the secondary holders having indicia indicating the different steps of progression in the operation and also having a symbol under the heading indicating 35 the ratio for the requirement indicated by the heading, in combination with an indicator for the current step in the operation.

10. The structure defined in claim 9 in which the card for each secondary card is 40 in two sections with the indicia on the one and the symbol on the other.

11. A chart for a given operation having different steps of progression including a panel having a main holder, and a plurality of secondary holders, said main and secondary holders being vertically spaced, a card in each holder, headings on the card in the main holder in a vertically spaced row and indicating different requirements for the operation, 45 the cards in the secondary holders having indicia indicating the different steps of progression in the operation and also having a symbol under each heading indicating the ratio for the requirement indicated by the 50 respective heading, in combination with an indicator for the current step in the operation.

In testimony whereof I affix my signature.
CHARLES E. NYGAARD.
